WINDOW

Mark E. Looney, Watertown, Mass.

Application September 6, 1933, Serial No. 688,311

8 Claims. (Cl. 20—49)

This invention relates to closure members, and more particularly to an improved window construction.

The principal object of the invention is to provide a window structure or the like which is of simple design and neat appearance; which is inexpensive to manufacture; which may be easily assembled and installed in either new or old structures; and which is so constructed that the sash or panel members may be readily manipulated and firmly held in any of a plurality of positions without disturbing or interfering with screening, awnings, or other objects disposed on the outside of the window.

Another object is to provide a window structure of weatherproof construction wherein the sash or panel members are designed for both sliding and pivotal movement and wherein the position of each sash or panel member may readily be reversed so that its exposed surface may be conveniently cleaned or repaired from the inside of the window, thus avoiding the dangers and inconvenience incident to cleaning and repair in the customary manner.

Further objects relate to the details of construction and to the operation of my improved construction and will be apparent from a consideration of the following description and accompanying drawings which exemplify one embodiment of the invention chosen for the purpose of illustration.

In the drawings:

Fig. 1 is an elevational view of the outside of a window constructed in accordance with the present invention;

Fig. 2 is a section on the line 2—2 of Fig. 1;

Fig. 3 is an enlarged fragmentary section on the line 3—3 of Fig. 2;

Fig. 4 is an enlarged fragmentary sectional view through the upper sash member, showing the normal position of the parts when the window is closed;

Fig. 4^a is a view similar to Fig. 4, but showing the position of the retaining strip when released;

Fig. 5 is an enlarged detail viewed from the line 5—5 of Fig. 4, showing the construction at the upper left-hand corner of the sash member;

Fig. 6 is an enlarged fragmentary section on the line 6—6 of Fig. 2;

Fig. 7 is an enlarged fragmentary sectional view through the lower sash member;

Fig. 8 is an enlarged fragmentary sectional elevation of a guide rod and associated locking means;

Fig. 8^a is a view similar to Fig. 8, but showing a modified construction;

Fig. 9 is an enlarged section on the line 9—9 of Fig. 8;

Fig. 10 is a longitudinal sectional view through the window, showing the panel or sash members in tilted position; and

Figs. 11, 12, 13 and 14 are diagrammatic sectional views, on a reduced scale, illustrating the various positions in which the panel or sash members may be adjusted.

Referring to Figs. 1, 2 and 10 the window construction shown therein comprises a frame or casement in which is slidably mounted a pair of sash or panel members A and B, each of which is of conventional construction. The casement comprises uprights 1 and 2, a sill 3, a top stile 4 having a recess 4^a on its under surface adjacent to each end, and an outer casing 5, the inner margins of which extend inwardly relative to the uprights 1 and 2, as shown in Figs. 3 and 6, to provide a retaining bead. The sill, stile and casing are of usual construction, and the usual weather strips may be provided at the top and bottom of the sash members A and B and, if desired, screening or the like designated by the numeral 6 in Fig. 10, may be provided on the outside of the sashes.

Each of the upright members 1 and 2, as shown in Figs. 3 and 6, is provided with a pair of spaced recesses 7 and 8 and a pair of spaced slots 9 and 10, the slots 9 and 10 being disposed closely adjacent to the recesses 7 and 8, respectively, and each of the slots and recesses preferably extend substantially the entire length of the uprights as shown in Figs. 2 and 10. The thickness of the lateral edges of each of the sash members A and B is greater than the combined width of the companion slots and recesses as will be apparent from inspection of Figs. 3 and 6.

Mounted in the recesses 7 and 8 are guide rails or rods 11 and 12 which are held in spaced relation to the walls of the recesses by spacer elements 14 and firmly secured at their ends by any suitable means such as screws 15. Runners, 45 designated generally by the numeral 20, are slidably mounted on the guide rods, as shown in Figs. 8, 8^a and 9, and each is freely movable along the rod and within the recess. For convenience, the runners associated with the upper sash A are 50 designated by the numeral 20^a and those associated with the lower sash B are designated by the numeral 20^b. Each runner is of substantially the same construction and comprises a tubular member 21 which surrounds the rod or rail and its 55

outer surface 22 is substantially flush with the surface of upright as shown in Figs. 4 and 7. The rear wall of the runner may extend either upwardly or downwardly beyond its body portion and may be provided with an opening 23 which forms part of a releasable locking device or latch designated by the numeral 25. The latch members associated with the upper sash are designated by the numeral 25^a and those associated with the lower sash by the numeral 25^b.

The locking device, as shown in Figs. 8 and 9, comprises a locking dog 26 which consists of a plate having an elliptical opening 27 which surrounds the rod 12 and an integral tongue 28 depending from its free end. The opposite end of the plate may be tapered slightly to fit loosely in the opening 23 of the rear wall of the runner so that the dog 26 may rock longitudinally of the rod 12 from locking position wherein it grips or engages the rod, to released position. The dog 26 is normally held in locking position by a coil spring 29 interposed between the dog and the end of the runner and surrounding the rod 12. The spring 29 is freely movable along the rod and is held compressed so as normally to urge or rock the dog into locking engagement with the guide rod 12.

The construction shown in Fig. 8 is such that upward movement of the runner tends to release the locking dog, causing it to swing downwardly so as to lose its grip on the rod, whereas attempted downward movement of the runner tends to rock or swing the locking dog upwardly, causing it to grip the guide rod 12 more firmly and thus lock the runner against downward movement. The locking dog may be released merely by pressing the tongue 28 inwardly toward the rod 12 thereby rocking the dog from locking position to released position wherein the runner may be freely slid along the guide rod. By transposing the position of the dog and spring on the opposite end of the runner, as shown in Fig. 4, the operation of the locking device may be reversed, that is, downward movement of the runner releasing the locking dog and attempted upward movement causing the locking dog to grip the guide rod, thus preventing upward movement of the runner.

As shown in Fig. 8^a, a positive interlocking engagement may be had by providing the guide rod 12^a with series of spaced notches 30. With this construction the locking dog 26, under the action of the spring 29, engages the notched portions of the guide rod and positively locks the runner against movement one way or the other along the rod. As indicated in Figs. 2 and 7 the runner and associated locking devices which are associated with the lower sash B preferably embody the arrangement shown in Figs. 8 and 9, whereas those associated with the upper sash A embody the reverse arrangement indicated in Fig. 4.

The runners 20^a and 20^b are pivotally connected to the sash members A and B, respectively, by links 32^a and 32^b. The length of each of the links is preferably of the order of one-half the length of the lateral edges of the sash members and each link is preferably connected to its respective sash member adjacent to the center of its lateral edge as shown in Figs. 10 to 14. When the window is closed, as shown in Figs. 1 and 2, the locking devices 25^a are disposed below the lower edge of the upper sash A, and the locking devices 25^b are disposed above the upper edge of the lower sash B, the runners and links being

concealed by the lateral edges of the sash members.

In the construction thus far described, the sash members A and B may not only be slid upwardly and downwardly in the casement, but may also be bodily swung out of the casement and rotated about their pivotal connections with the links. In order to confine the sash members within the casement and still permit the aforementioned sliding and pivotal movement of both sash members, releasable retaining means are provided for holding each of the sash members within the casement. To this end the lateral edges of the upper sash A are provided with longitudinally extending slots 35 (Figs. 3 and 4) which are juxtaposed to and communicate with the slots 9 in the uprights, and the lateral edges of the lower sash B are likewise provided with similar slots 36 (Figs. 6 and 7) communicating with the slots 10. Retaining strips 40^a and 40^b of metal or other suitable material are disposed in the slots 35 and 36, respectively, and are supported adjacent to their ends by links 42 and 43 which are pivotally connected at their inner ends to the sash members by screws 44 and at their outer ends to the retaining strips by rivets or other suitable means. The retaining strip, links and the edge of the sash constitute, in effect, a four-bar or parallel motion linkage system wherein the movement of the retaining strip, in response to pivotal movement of the links 42 and 43, is always parallel to the edge of the sash. The width of the retaining strips is approximately equal to or slightly less than the depth of the slots 35 and 36 so that when the strips are in nested or released position, as shown in Fig. 4^a, they lie within the slots in the sash members, and when in extended position they project into the slots 9 and 10, as shown in Figs. 3, 4 and 6. Movement of the strips from one position to the other is effected by means of a lever or thumb-piece 38 which may be secured to the top link 42 or the upper end of the retaining strip so as to be conveniently disposed on the upper edge of the sash member. As shown in Figs. 2 and 4, the thumb-pieces 38 on the upper sash A are disposed within the pockets 4^a in the stile 4 when the sash is fully closed.

The retaining strips preferably extend substantially the entire length of the lateral edges of the sash and snugly fit within the respective slots so as to prevent objectionable wobbling of the sash and insure a smooth sliding movement. With this construction the retaining strips provide guiding means which confine the movement of the sash to a rectilinear path within the casement and also provide weather strips on each of the lateral edges of the sashes.

The operation of my new window construction is as follows:

With the sash members A and B fully closed as shown in Figs. 1 and 2 and the retaining strips 40^a and 40^b in extended position, the sash A is held against downward movement by the latch devices 25^a and may be lowered to any desired position by exerting a downward pressure on its frame sufficient to release the grip of the locking dogs on the guide rods, and in similar manner the lower sash B may be raised by pressing upwardly on its frame. When the sash A is thus lowered, the latch devices 25^a, as previously noted, prevent upward movement and consequently in order to raise or close the sash it is necessary to release the latch devices by pressing their tongues upwardly. This may be conven-

iently accomplished by applying the force necessary to raise the sash on the tongues, the force thus applied being effective to release and hold it in released position the latch devices while the window is being raised. When the pressure on the latch devices is released the locking dogs assume their normal position and grip the guide rods sufficiently to hold the sash in any desired position.

10 The operation of the lower sash B is substantially the same as the upper sash except that the latch devices 25^b may be released sufficiently, by upward pressure, to permit the sash to be raised, and in order to lower or close the sash the latch devices must be manually released and so held while lowering.

In order to swing the sash members out of the casement, it is merely necessary to release the retaining strips from their extended positions, whereupon the sash members may be swung bodily from the casement. For example, to remove the upper sash from the casement it is first lowered sufficiently to permit access to the thumb-pieces 38, so that the retaining strips 40^a may be swung to nested position, and the sash may then be swung from approximately the position shown in Fig. 2 to any desired position, such for example, as the position shown by the broken lines in either Fig. 10 or 13. In similar manner the lower sash may be swung from the casement into any of a plurality of positions as indicated by the broken lines in Figs. 10 and 11. By raising or lowering the runners, the angular position of the sash members relative to the casement, as well as their positions relative to each other, may be varied throughout a wide range of positions as indicated in Figs. 11 to 14.

In the particular embodiment herein shown the inwardly projecting margins of the casing 5 (Figs. 3 and 6) serve as abutments which support the bottom edges of the sashes when in tilted position and thus prevent them from being swung outwardly. The frictional engagement between the casing 5 and the bottom edges of the sashes is usually sufficient to hold the sash in tilted position, although, if desired, various expedients may be adopted for accomplishing this, for example, by providing the marginal portion of the casing 5 with notches 45, as shown in Fig. 13, which receive the corner portions of the sashes and thus securely hold them in the desired position.

The various positions into which the panel or sash members of a window or the like closure, constructed in accordance with the present invention, may be adjusted and held is particularly advantageous in dwellings and office buildings in that the sashes may be adjusted so as to provide a "no-draft" ventilation arrangement, as will appear from an inspection of Figs. 11 and 12. Furthermore, the sashes may be reversed so that their outer surfaces face inwardly, as shown in Fig. 14, and hence cleaning or repair work may be done conveniently from the inside without disturbing or removing screening or other objects disposed on the outside of the sashes, and thus the dangers and inconvenience incident to cleaning and repair in the customary manner are avoided.

70 Moreover, a window constructed in accordance with the present invention dispenses with the necessity of using window weights and associated adjuncts, all of which appreciably increase the cost of manufacture of the window and the installation thereof. The window construction

herein shown may be easily and quickly installed as a unit in either new or old buildings and may be made in various sizes, shapes, etc.

While I have shown and described one desirable embodiment it should be understood that the present disclosure is for the purpose of illustration only and that various changes in shape, arrangement and proportion of parts, as well as the substitution of equivalent elements for those herein shown and described, may be made without departing from the spirit and scope of the invention as set forth in the appended claims.

I claim:

1. A window construction comprising relatively movable frame and sash members, guiding means including a rail secured to one of said members and a runner slidable thereon, means for locking said rail and runner in relatively fixed position, a link pivotally secured at one end to said runner and pivotally connected at its opposite end to the other of said members, and releasable retaining means operative to hold the sash member within the frame member.

2. A window construction comprising a frame, a sash member movable within said frame, a rail secured to said frame, a runner slidably mounted on said rail, yieldable means carried by said runner for locking said runner to said rail, a link pivotally secured at one end to said runner and at its opposite end to said sash member, and releasable retaining means operative to hold the sash member within said frame.

3. A window construction comprising a frame, a sash movable within said frame, a guide rail secured to said frame, a runner slidably mounted on said rail, yieldable means carried by said runner for locking the runner to said rail, a link pivotally secured at one end to said runner and at its other end to said sash, and releasable means for obtaining said sash within said frame, said latter means being constructed and arranged to confine the movement of said sash to a rectilinear path when in normal position and upon release permit the sash to be swung from said frame.

4. In a construction of the class described, the combination of a frame, a panel member slidable therein, a guide rail secured to said frame, a runner connected to said panel and slidably mounted on said rail, and releasable means for holding said runner in fixed position relative to said rail, said means comprising a locking dog embracing said rail and pivotally mounted on said runner to rock from locking position wherein it grips said rail to released position, and a spring member acting upon said dog normally to hold it in locking position, said locking dog and spring being so constructed and arranged that movement of said runner in one direction releases the locking action of said dog and movement of said runner in the opposite direction cooperates with the action of said spring to effect locking action of said dog.

5. In a window construction, the combination of a frame having a longitudinally extending recess, a sash slidable in said frame, a guide rod disposed in said recess, a runner slidably mounted on said rod within said recess and connected to said sash, and releasable means for locking said runner to said rod comprising a locking dog embracing said rod and pivotally mounted on said runner to rock from locking position wherein it grips said rod to released position, a coil spring surrounding said rod and slidable with said runner, said spring acting upon said dog and nor-

5 mally holding it in locking position, said locking dog and spring being so constructed and arranged that movement of said runner in one direction releases the locking action of said dog and movement 10 of said runner in the opposite direction cooperates with the action of said spring to effect locking action of said dog, and means connected to said dog for rocking it from locking position to released position.

10 6. In a window construction, the combination of a frame having a longitudinally extending recess, a sash slideable in said frame, a guide rod having a plurality of notched portions disposed in said recess, a runner slidably mounted on said 15 rod within said recess and connected to said sash, and releasable means for locking said runner to said sash comprising a locking dog embracing said rod and pivotally mounted on said runner to rock from locking position wherein it engages one 20 of the notched portions of said rod to released position wherein it clears said notched positions, a spring member carried by said runner and normally acting upon said dog to urge it toward locking position, said locking dog and spring being so 25 constructed and arranged that movement of said runner in one direction releases the locking action of said dog and movement of said runner in the opposite direction cooperates with the action of said spring to effect locking action of said dog, and releasing means carried by said dog, said 30 means being operative to rock said dog from locking position to released position.

7. A window construction comprising a frame, a sash slideable in said frame, a guide rail secured to said frame, a runner slidably mounted on said rail, locking means for holding said runner in fixed relation to said guide rail, a link pivotally secured at one end to said runner and at its opposite end to the side of said sash adjacent to its center, the length of said link being of the order of one-half the length of said sash thereby to permit the sash to swing out of said frame into 10 reversed position, and releasable retaining means constructed and arranged to hold said sash within said frame.

8. A window construction comprising a frame having a longitudinally extending recess in each 15 side, a sash slideable in said frame, a guide rail disposed in each recess, a runner slidably mounted on each guide rail, releasable means for locking each runner and guide rail in fixed position, releasable retaining means for holding said sash 20 and confining its movement to a rectilinear path within said frame, and a pair of links each of which is pivotally connected at one end to a runner and at its other end to one side of the sash, the length of said links being such as to 25 permit the sash to be swung out of the frame, upon release of said retaining means, and held in any of a plurality of positions into which it may be swung and/or tilted.

MARK E. LOONEY. 30
